UNITED STATES PATENT OFFICE.

FREDERICK F. STREET, OF HARTFORD, CONNECTICUT.

DRY CLOSET.

SPECIFICATION forming part of Letters Patent No. 301,018, dated June 24, 1884.

Application filed January 21, 1884. (No model.)

To all whom it may concern:

Be it known that I, FREDERICK F. STREET, of Hartford, in the county of Hartford and State of Connecticut, have invented a new and useful Improvement in Dry Closets, of which the following description and claims constitute the specification, and which is illustrated by the accompanying drawing.

The figure shown is a side view of an apparatus embodying my improvement.

This invention is particularly adapted to the closets of railroad-cars. Its function is to close the lower end of the discharge-chamber of such a closet whenever the upper end is covered by a user, and thus to prevent access of cold air to the person of the occupant.

A in the drawing is a discharge-chamber of ordinary construction, except that its lower end, instead of being cut off at right angles to the axis of the chamber, is cut off diagonally, as shown in the drawing.

B is an elliptic disk large enough to close the lower end of the discharge-chamber when shut against the latter.

C is an anvil rigidly attached to or forming a part of the disk.

D is a lever of the first order, the weight end of which is rigidly fastened to the disk B, and the fulcrum of which is pivoted to an arm attached to the discharge-chamber.

E is a connecting-rod, the lower part of which is encircled by the spiral spring F. The spring is held against upward movement by the nut G, working on a screw-thread on the rod E, and it is supported from below by the journaled and perforated rest H. The journals of that rest turn in journal-boxes in the forked power end of the lever D. The lower end of the rod E passes through the per-

foration in the rest H, and below the rest the rod is furnished with the nut I. The upper end of the rod is pivoted to the arm K by a pivot, J, which passes through the forked lower end of that arm, and which works in a slot in the upper end of the rod E. The arm K is rigidly attached at its upper end to the seat-lid L.

The mode of operation of this apparatus is as follows: When the closet is not being used,

the parts are in the positions shown in the dotted lines. When the user raises the seat-lid, the arm K forces down the rod E, and that rod, through the nut G, the spring F, and the rest H, forces down the power end of the lever D, and forces up the disk B, so that the latter will close the lower end of the discharge-chamber. Thereupon any excrement which falls through the discharge-chamber, when it strikes the upper surface of the disk B, will tend to slide down that surface till it reaches the part directly over the anvil C. When the user rises from the seat, he closes the seat-lid. The slot in the upper end of the rod E allows the lid to be nearly closed down upon the seat before the disk B is removed from the lower end of the discharge-chamber, and in so doing enables the lid to arrest the upward motion of any paper that otherwise might be blown backward and into the room occupied by the closet. When the seat-lid is entirely closed down, the disk B will again be in the position shown in the dotted lines. Then, if any excrement adheres, by freezing or otherwise, to the upper surface of the disk B, it may be dislodged by a blow of a hammer upon the anvil C. The connection between the rod E and the lever D is an elastic, and not simply a pivotal, one, to the end that any matter frozen or otherwise adhering to the upper surface of the disk B will not prevent the complete raising of the seat-lid.

I claim as my invention—

1. The combination of the discharge-chamber A, the disk B, the lever D, the rest H, the spring F, the rod E, furnished with the nuts G and I, and the seat-lid L, furnished with the arm K, all combined and operating together substantially as described.

2. The combination of the rod E, the nuts G and I, the spring F, the rest H, and the lever D, and means for operating the same, substantially as described.

FREDERICK F. STREET.
